Primary Examiner — Ian Simmons*Assistant Examiner* — Carissa C Fitts(74) *Attorney, Agent, or Firm* — Fraser Clemens Martin & Miller LLC; William J. Clemens(57) **CLAIM**

The ornamental design for a rechargeable LED floodlight, as shown and described.

DESCRIPTION

FIG. 1 is a front perspective view of rechargeable LED floodlight showing our new design;

FIG. 2 is a front elevation view thereof;

FIG. 3 is a rear elevation view thereof;

FIG. 4 is a top plan view thereof;

FIG. 5 is a bottom plan view thereof;

FIG. 6 is a left side elevation view thereof; and,

FIG. 7 is a right side elevation view thereof.

The broken line showing in the drawings represents unclaimed portions of the design article and forms no part of the claimed design.
